UNITED STATES PATENT OFFICE.

JAMES A. HOUSTON, OF BOSTON, MASSACHUSETTS.

STORE.

SPECIFICATION forming part of Letters Patent No. 276,587, dated May 1, 1883.

Application filed February 26, 1883. (No model.)

To all whom it may concern:

Be it known that I, JAMES ALBERT HOUSTON, of Boston, in the county of Suffolk, of the State of Massachusetts, have invented a new and useful Improvement in Stores or Furniture thereof; and I do hereby declare the same to be described in the following specification and represented in the accompanying drawings, of which—

10 Figure 1 is a side elevation of two sets of goods-shelves of a store, their receiving-station, "cash-boys' gallery," and bridge arranged in accordance with my invention, the nature of which is defined in the claims hereinafter presented. Fig. 2 is a vertical and transverse section taken through one set of shelves and the station, such section also showing sections of the counters arranged in front and rear of the set of shelves. Fig. 3 is a transverse section 15 of the set of shelves and the cash-boys' gallery over it. Fig. 4 is a transverse section of the bridge.

In stores wherein goods are sold by retail and many persons usually congregate at times 20 for the purchase of such goods, it has been the custom for several years to employ messengers or boys termed "cash-boys," whose duty is to receive from the salesmen money paid them for and on accounts of sales and transmit 25 them to the desk of the cashier, and to receive from him any change and take it to the salesman, to be given by him to the customer. When there may be a crowd or large number 30 of persons or buyers in front of the counters and in the aisles of the store, it often becomes 35 very difficult for the cash-boys to pass along from the salesmen to the cashier and back without inconvenience both to such boys and to the customers.

40 My invention is to provide, in connection with the sets of goods-holding cases or shelves, counters, and the aisles of a store, means by which the cash-boys can pass to and fro, as occasion may require, without going upon the 45 floor among and incommoding the customers who may be in front of the counters or in the aisles or passages; and for this purpose I combine with the set or sets of shelves for holding goods on sale one or more galleries or walks 50 arranged directly over them, and leading from them to one or more receiving stations; and when there may be on the floor an aisle or

passage-way extending between two or several sets of such shelves or goods-cases, and it may be desirable or necessary for the messengers or cash-boys to cross such aisle, I have the galleries of the sets connected by one or more bridges, each leading from one set of shelves on one side of the aisle to another set of them on the opposite side of such aisle, all being substantially as hereinafter described.

In the drawings, A A' denote two sets of store-shelves, and B an aisle between them, there being in front of each of such sets a counter, C, or one in front and another in rear 65 of the set, and arranged therewith in the usual manner. Each set of shelves, or what is often termed "shelving," is to be constructed as represented or in any other proper manner; or it may be a goods-case provided with doors 70 having glass panes in them. It is to be about the height that a person of medium size can conveniently reach to in order for him to hand goods or parcels to the cash-boys or to place such goods on the floor of the gallery or on a 75 shelf, a, extended from the gallery, as shown.

The gallery or walk over one of the sets of shelves is represented at D, as provided on its sides with railings b b, such gallery, by means of a bridge, E, extending over the aisle 80 B, being connected to another such gallery or to a station, F, arranged on and over the opposite set of shelves. This station is shown in transverse section in Fig. 2 as an inclosed space provided with shelves c c' and counters 85 d d', arranged as represented. The station I usually provide with pneumatic tubes or mechanical means by which single parcels or packages may be rapidly conveyed from it to the cashier's department, and returned therefrom.

From the above it will be seen that after having effected at his counter a sale of any article and received money therefor, a salesman is to hand the money or article, or both, and a 95 certificate giving details of the sale, to a messenger or cash-boy in the gallery, or is to place the matter on the gallery-shelf a, for it to be subsequently removed therefrom by such messenger or cash-boy in the gallery. The messenger 100 or boy, having received the package or packages, next passes along the gallery to the station and delivers the same to one or more attendants there, from whom he receives the

money or matter to be returned and carries such to the salesman.

I claim--

5. 1. A set of shelves or a case for holding goods or merchandise for sale, provided with a gallery for cash-boys, arranged with it in manner and for the purpose substantially as set forth.
10. 2. A set of shelves or a case for holding goods or merchandise for sale, provided with a station and a gallery for cash-boys, all being substantially as set forth.
15. 3. Two sets of shelves or two goods-cases arranged on opposite sides of an aisle or passage-way, and provided with galleries and a bridge connecting them, such bridge crossing the aisle, and each gallery being arranged along the tops of the two sets of shelves or two goods-cases, as and for the purpose substantially as explained.
20. 4. Two sets of shelves or two goods-cases

arranged on opposite sides of an aisle or passage-way, and provided with one or more stations and one or more galleries, and a connecting-bridge, all substantially and arranged 25 as set forth.

5. A set of shelves arranged between two counters, and provided with a gallery extending along over the uppermost shelf, substantially as and for the purpose set forth. 30

6. Two sets of shelves arranged on opposite sides of an aisle, and not only provided with galleries and a connecting-bridge thereto for cash-boys or messengers, as set forth, but having counters arranged on opposite sides of 35 and with each set of shelves, substantially as specified.

JAMES ALBERT HOUSTON.
